UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

MULTIPLE-NEEDLE SINGLE-CHAIN-STITCH MACHINE.

1,118,574.

Specification of Letters Patent.

Patented Nov. 24, 1914.

Application filed October 30, 1907. Serial No. 399,831.

To all whom it may concern:

Be it known that I, LANSING ONDERDONK, a citizen of the United States, residing at New York, in the county of New York, State of New York, have invented certain new and useful Improvements in Multiple-Needle Single-Chain-Stitch Machines, of which the following is a description, reference being had to the accompanying drawings and to the letters and figures of reference marked thereon.

My invention relates to new and useful improvements in sewing machines, and more especially sewing machines of the character wherein a plurality of needles and a plurality of non-thread-carrying loopers are used, which coöperate with said needles in forming single chain stitches. It will be obvious, however, that from certain aspects, my invention is not restricted to a plurality of needles and loopers, nor to a looper of the non-thread-carrying type.

The object of my invention is to provide a stitch-forming mechanism wherein a plurality of lines of stitching may be made at a considerable distance apart.

A further object of my invention is to provide a mechanism for operating a looper, whereby said looper may be given a relatively quick movement into the needle loop, and wherein said looper is for the greater part of its movement, in the needle loop.

Further objects of my invention will in part be obvious, and in part be hereinafter more fully set forth.

In the drawings which show by way of illustration one embodiment of my invention;—Figure 1 is a front elevation with parts in section showing a machine having my improved stitch-forming mechanism applied thereto; Fig. 2 is an end view of the same, with the bed plate removed, and certain parts in section; Fig. 3 is a top plan view of the forward end of the machine, showing the parts beneath the work support, the feed dogs being broken away; Fig. 4 is a detail, showing the relative position of the needle and looper, when the looper is at the rear end of its stroke; Fig. 5 is a similar view, with the driving shaft given a quarter turn; Fig. 6 is a similar view, with the looper in its forward position; and Fig.

7 is a similar view, showing the driving shaft having been given a three-quarter turn.

The bed plate 1 has rising therefrom the usual overhanging arm 2, on which is pivotally mounted a needle lever 3, which is oscillated from the main shaft 4, by means of the usual link 5. The needle bar 6 is mounted to reciprocate in bearings in the forward end of the overhanging arm, and carries a needle head 7 at its lower end. In said needle head is mounted, as shown in the present embodiment of my invention, four needles 8, 8, and 9, 9. Said needles, as clearly shown in Fig. 1, are arranged in pairs at the outer end of the needle head 7. It is obvious, however, that the needles may be disposed in any desired manner upon the needle head, and that any number of needles may be substituted for the four needles herein shown, without in any way departing from the spirit of my invention.

The presser foot 10 is mounted on the usual presser bar 11, which may be lifted by a presser bar lever 12. Said presser foot 10 is shown as provided with an adjustable guiding finger 13 at each end thereof, between which a strip may be guided and stitched to a fabric when desired.

The feed bar 14 is pivoted to the usual feed rocker 15, which is oscillated by an eccentric strap 16, carrying a ball stud 17, which engages the outer end of an arm 18 rigidly secured to the rocking frame 15. The eccentric strap 16 engages an eccentric on the main shaft 4. Said eccentric is secured to a disk 19, which in turn is secured to a collar 20 mounted on the main shaft 4. The disk 19 may be adjusted across the face of the collar 20, for the purpose of varying the movements of the rocking frame 15. The feed bar at its forward end carries a slotted head 21, on which are adjustably mounted feed dogs 22, 23 and 24. Said feed dogs are secured in their adjusted position by suitable screws. The feed dogs receive their up and down movement from a suitable eccentric 40, secured to the main shaft 4, and engaging the feed bar 14, in the usual manner.

Coöoperating with the needles 8, 8, are two loopers 25, 25, each of which is supported in

a looper carrier 26, clamped to a looper supporting rod 27, by means of a clamping screw 28. Coöperating with the needles 9, 9, are loopers 29, 29, each of which is mounted in a carrier 30, secured to the looper-supporting rod 27, by means of the clamping screw 31.

The looper supporting rod 27 extends parallel to the main shaft 4, and is mounted 10 in suitable bearings in the brackets 32 and 33, which also serve as bearing supports for the main shaft 4. The looper supporting rod 27 has a collar 34, secured thereto at one end, and at its opposite end an arm 35 is 15 clamped thereon by means of screws 36, 36.

The arm 35 is forked at its outer end, and embraces one end of a link 37, which is pivotally connected at its opposite end to a crank pin 38. Said crank pin 38 is mounted 20 on the outer end of a crank arm 39, which is secured to the outer end of the main shaft in any suitable manner.

The needle threads are led through suitable tensions 41, and thence through suitable 25 thread guides 42, 43 and 44, to the thread guide 45 at the upper end of the needle bar. The needle threads are then led through suitable guiding eyes 46 in the needle head 7 to the respective needles.

30 The operation of my device will be apparent from the above description. As the main shaft rotates, the needle is reciprocated through the needle lever 3, and the loopers are oscillated through the crank pin 38 and link 37, which operates the looper supporting rod 27. It will be noted that the looper when in its extreme rearward position, as shown in Fig. 4, is only slightly in the rear of the needle. At this time the crank pin 40 38 is passing the dead center, and, therefore, the looper is given an extended dwell. The needle is at this time at the lower end of its stroke, and after the same has risen slightly to throw out the needle loop the 45 looper moves forward into said needle loop and by the time the main shaft has been given a quarter turn the point of the looper is well into the needle loop, and the needle has risen so that the eye thereof is slightly 50 above the looper. The looper continues its forward movement until the main shaft has been given a half turn, and at this time the needle has reached substantially the upper end of its stroke, as shown in Fig. 6. At 55 this time the looper is given a slight dwell, owing to the fact that the crank pin is again on the dead center. The needle then descends for the new stitch, the feed having taken place while the needle was on the 60 upper portion of its stroke, and the looper meanwhile slightly retracts, but the enlarged portion 47 on the under side of the looper serves to retard the needle loop

formed on the previous stroke of the needle, so that the point of the needle enters said 65 needle loop carried by the looper.

The loopers as shown in Fig. 1, may be so constructed as to work upon opposite sides of the needles, thus allowing the needles to be placed very closely together. 70 It will be also noted that the looper moves in the direction of the feed, and that the needle loops, therefore, supported by the loopers will extend from the previous needle puncture around the shank of the looper 75 and thus be spread or properly positioned for the entrance of the needle into the needle loop on the looper.

It will be obvious that the loopers and needles may be positioned so as to form 80 rows of stitches a considerable distance apart, and also so as to form practically any number of rows of stitches within certain limits.

By my particular form of looper-operating mechanism, the looper is given a dwell at the rear end of its stroke, and is then moved forward with increasing speed until the same has entered well into the needle loop, after which the speed of the looper 90 decreases, and an extended dwell is given at the forward end of the stroke of the looper. The movements of the looper on the retracting stroke are substantially the same as those on the forward stroke. 95

Having thus described my invention, what I claim as new and desire to secure by Letters Patent, is:—

1. The combination of a work support, a main shaft located beneath the work support, a looper supporting shaft in front of said main shaft, a plurality of loopers carried by said looper supporting shaft, spaced bearings in which said looper supporting shaft is mounted, a crank arm carried by 100 the forward end of said looper supporting shaft, a crank pin carried by the end of the main shaft, and a link for connecting said crank arm and said crank pin. 105

2. The combination of a work support, a main shaft located beneath the work support, a looper supporting shaft in front of said main shaft, a plurality of loopers carried by said looper supporting shaft, means for independently adjustably connecting 110 said loopers to said looper supporting shaft, spaced bearings in which said looper supporting shaft is mounted, a crank arm carried by the forward end of said looper supporting shaft, a crank pin carried by the 115 end of the main shaft, and a link for connecting said crank arm and said crank pin. 120

3. The combination of a work support, a main shaft located beneath the work support, a looper supporting shaft in front of 125 said main shaft, a plurality of loopers car-

ried by said looper supporting shaft, means for independently and adjustably connecting said loopers to said looper supporting shaft, spaced bearings in which said looper supporting shaft is mounted to oscillate back and forth without endwise movement, a crank arm carried by the end of the looper supporting shaft, an eccentrically disposed member on said main shaft, and means for

oscillating said crank arm from said eccentric member. 10

In testimony whereof I affix my signature, in presence of two witnesses.

LANSING ONDERDONK.
